PANEL BEND

Elmo E. Alexander, New Albany, Ind.

Application February 16, 1939, Serial No. 256,654

3 Claims. (Cl. 144—309)

This invention relates to the formation of a bend in a veneer panel and has for a primary object the employment of a structure as a method of forming the structure into a bend that will give a smooth curve and be sufficiently strong that outside posts or other supporting elements may be dispensed with. It is a further important object of the invention to form a bend that will be exceedingly simple in structure and that will permit production without intricate machines or steps so that the cost of production may be relatively low.

These and other objects and advantages of the invention will become apparent to those versed in the art from the following description of one particular form as illustrated more or less diagrammatically in the accompanying drawing, in which

Fig. 1 is a view in side elevation of the various parts in disassembled relation required to form the bend;

Fig. 2, an edge elevation in assembled relation; Fig. 3, a plan view with the inner back and cross bands broken away; and

Fig. 4, an end elevation of the completed bend.

Like characters of reference indicate like parts throughout the various views in the drawing.

A core 10 is initially built up from any suitable material following the usual procedure well-known to those versed in the art. The core as a rule is generally built up from a number of pieces of wood glued together to form a core of the desired approximate thickness. The core 10 is cut away and a core insert 11, made out of suitable wood, is inserted and glued into place. This core insert 11 has a thickness less than that of the core 10 and is backed up by a spline of wood 12 or other suitable resilient material such as fabric, rubber, and the like, to bring the combined thickness of the insert 11 and the spline 12 to equal the thickness of the core 10. A face cross band 13 is glued to the core 10 and the outer side of the spline 12, the insert 11 being glued by its ends and its outer face respectively to the abutting ends of the core 10 and the inner face of the spline 12. The cross band 13 is then covered by a face ply or band 14 to give the desired external finish face.

After these various members are thus assembled the insert 11 is cut across the area to be bent by a plurality of relatively closely spaced slots 15. The transverse slots 15 may, of course, be cut prior to the application of the cross band 13 and the face band 14, the exact sequence of

these steps being immaterial and subject to the practice within the local shop.

After the insert 11 has been slotted, a back cross band 16 has an adhesive applied over its area to contact the core 10 up to some such zone B, Fig. 4, but the adhesive is omitted over the remaining area of the band 16 which will be over the slotted portion of the insert 11. The back cross band 16 having the adhesive thus applied is placed over the core to carry this cross band 16 from one part of the core 10 across the insert 11, to have the adhesive secure the cross band 16 to the core 10 to one side of the insert 11 but leaving the cross band 16 entirely free from adhesion to the insert 11 particularly over that area thereof which carries the slots 15. Then the back face band 17 is placed over the cross band 16 and secured thereto by any suitable adhesive. The panel thus formed is taken to the bending machine, glue or adhesive is sprayed under the cross band 16 by lifting it up as indicated in Fig. 2; the band 16 and its adhering band 17 dropped down onto the insert 11; and the panel then is bent in the usual manner before the glue sets to assume that form as indicated in Fig. 4 or any other degree of curvature as may be desired. The underfolded section 16 is less in length than the top section 17, and has a length substantially equal to one-half of the length of the slotted area of the core 10. Referring to Fig. 4, it will be noted that the segments of the insert 11 between adjacent slots 15 come together by their inner ends and the cross band 16 fits snugly across and against their faces.

In the bending operation, the resilient spline 12 supports the individual segments between slots 15 of the insert 11, and, being of a resiliently yielding nature, permits the corners of those segments adjacent the spline to press into the spline while the outer cross band 13 and face band 14 bend around in a uniform curve without the lines of those segment corners defining transverse lines on the face band 14. Also, as the bend is formed, the back band 17 with its cross band 16, being initially free and lubricated with the freshly applied adhesive, travel relatively longitudinally around over the insert 11 to have their ends shift a distance such as from A to C, Fig. 4, these points, of course, being varied depending upon the lengths of those bands as originally employed.

Then, after the bending has taken place, the bend is held under pressure until the adhesive sets between the face band 17 and the back band

16 and between the back band 16 and the insert 11 and core 10 over which it laps. The band 16 then adheres intimately over the back faces of the insert segments, the remainder of the insert 11, and the lapped over part of the core 10. The back band 17, in the finished bend will present a smoothly curving surface without any apparent bend lines, the width of the segments of the insert 11 between slots 15 being relatively small.

Referring to the back cross band 16 in its initial state before having adhesive applied to it, and before being placed over and on the core 10, this cross band 16 is cut through along the line D—D and then rejoined by means of a narrow band of paper 18 (any flexible, thin fabric will do) adhesively lapped over marginal portions of the band 16 adjacent the line D—D. This paper 18 forms a hinge, and the outer portion of the band (left-hand side in Fig. 2) is swung around and against the under or inner face of the band 16. With this band 16 thus folded, adhesive is applied over the under face of the band and over the folded section, thereby causing that part of the under face of the band 16 covered over by the folded over section to be left free of adhesive, and also causing the then inner face of that folded section to be left free of adhesive. Then the folded section of the band is unfolded to swing it around into its original plane with the major part of the band 16. There will then be an area of adhesive on the top or outer side of that unfolded section which will contact the inner face of the band 17 when it is applied thereunder. The primary purpose of initially folding under that section of the band 16 is to keep adhesive off of that area of the band 16 which is to extend across the core insert 11, while the band 16 is first being applied to the core 10. After the band 16 has received its under face adhesive coating and the underfolded section straightened out, the band 16 is placed over the core 10, to have its under adhesive side placed to one side of the insert 11 as heretofore indicated, to have the uncoated area extend over the insert 11. Then the back cross band 17, suitably coated by adhesive over its entire inner face, is placed adhesive face down on the band 16 and pressed thereagainst. That area of the unfolded section of the band 16 which was originally coated by adhesive when folded under the band 16, of course presents that same adhesive coated area on the outer or upper side when the section is unfolded, to have that area contact with the adhesive coated face of the band 17—both bands 16 and 17 thus being each initially coated over that folding section area. The sole purposes of the initial folding under of the end portion of the band 16 are to prevent initial coating of the fold inclosed area and to permit the band to receive its adhesive easily by passing it in folded condition straight through a glue applying machine.

While I have herein shown and described my invention in the one best form as now known to me, it is obvious that structural changes may be employed, such for example as employing V-slots in place of the rectilinear slots 15, without departing from the spirit of the invention, and I,

therefore, do not intend to be limited to that precise form beyond the limitations that may be imposed by the following claims.

I claim:

5. For a ply-wood bend, a panel having a core, comprising an insert in the core, and a spline across and adhering to the insert, said spline having a greater degree of resiliency than that of said insert, a band adhering to said spline, said insert being provided with a plurality of transverse, spaced slots entering the insert from its side opposite the spline side, and a back band 10 adhering to said core on its face removed from said first band and to one side of said insert and extending therefrom loosely across at least the slotted area of said insert, whereby the loose portion of the back band may receive adhesive and be free to travel longitudinally relatively over the insert when the bend is formed, said back band being in two parts divided within the length of the slotted area of the insert, and a length of thin flexible material hinging the divided parts of the back band together.
10. For a ply-wood bend, a panel having a core, the core in a bending zone of the panel being reduced in thickness, a spline joined with the core to extend at least across said reduced thickness portion, said portion having relatively closely spaced slots extending thereacross opening on the opposite side from the spline, a face band 15 adhesively secured over said core and spline, a back band adhesively joined to said core and having an end portion extending from the joined portion loosely over said slotted area of the core 20, said back band being in two parts divided within the length of the slotted area of the insert, and a length of thin flexible material hinging the divided parts of the back band together.
25. For a ply-wood bend, a panel having a core, the core in a bending zone of the panel being reduced in thickness, a spline joined with the core to extend at least across said reduced thickness portion, said portion having relatively closely spaced slots extending thereacross opening on the opposite side from the spline, a face band 25 adhesively secured over said core and spline, a back band adhesively joined to said core and having an end portion extending from the joined portion loosely over said slotted area of the core 30, said back band being in two parts divided within the length of the slotted area of the insert, and a length of thin flexible material hinging the divided parts of the back band together.
30. That method of forming plywood for a bend which comprises forming a plurality of slots across a core parallel to the axis of curvature of the intended bend, hinging one section to another of a band by a thin flexible sheet of material, folding one band section back under the other, the underfolded section being less in length than the top section, applying an adhesive over the underside of the folded section and also a portion of the underside of the top section whereby the areas of the underside of the top section covered over by the folded section and of the then inner side of the folded section are left free of adhesive, the said underfolded section having a length substantially equal to one-half of the length of the slotted area of said core, unfolding said underfolded section to swing its adhesive coated side around to be then on its top side, placing said unfolded band with its under adhesive coated area on said core to one side of the core slotted area to have the uncoated underside areas of said band sections extend over said core slotted area, and placing a second band over the first band with an adhesive applied over the area therebetween to have the second band overlap said hinge material and to have the second and first bands become adhesively secured one to the other.
35. That method of forming plywood for a bend which comprises forming a plurality of slots across a core parallel to the axis of curvature of the intended bend, hinging one section to another of a band by a thin flexible sheet of material, folding one band section back under the other, the underfolded section being less in length than the top section, applying an adhesive over the underside of the folded section and also a portion of the underside of the top section whereby the areas of the underside of the top section covered over by the folded section and of the then inner side of the folded section are left free of adhesive, the said underfolded section having a length substantially equal to one-half of the length of the slotted area of said core, unfolding said underfolded section to swing its adhesive coated side around to be then on its top side, placing said unfolded band with its under adhesive coated area on said core to one side of the core slotted area, and placing a second band over the first band with an adhesive applied over the area therebetween to have the second band overlap said hinge material and to have the second and first bands become adhesively secured one to the other.
40. That method of forming plywood for a bend which comprises forming a plurality of slots across a core parallel to the axis of curvature of the intended bend, hinging one section to another of a band by a thin flexible sheet of material, folding one band section back under the other, the underfolded section being less in length than the top section, applying an adhesive over the underside of the folded section and also a portion of the underside of the top section whereby the areas of the underside of the top section covered over by the folded section and of the then inner side of the folded section are left free of adhesive, the said underfolded section having a length substantially equal to one-half of the length of the slotted area of said core, unfolding said underfolded section to swing its adhesive coated side around to be then on its top side, placing said unfolded band with its under adhesive coated area on said core to one side of the core slotted area, and placing a second band over the first band with an adhesive applied over the area therebetween to have the second band overlap said hinge material and to have the second and first bands become adhesively secured one to the other.
45. That method of forming plywood for a bend which comprises forming a plurality of slots across a core parallel to the axis of curvature of the intended bend, hinging one section to another of a band by a thin flexible sheet of material, folding one band section back under the other, the underfolded section being less in length than the top section, applying an adhesive over the underside of the folded section and also a portion of the underside of the top section whereby the areas of the underside of the top section covered over by the folded section and of the then inner side of the folded section are left free of adhesive, the said underfolded section having a length substantially equal to one-half of the length of the slotted area of said core, unfolding said underfolded section to swing its adhesive coated side around to be then on its top side, placing said unfolded band with its under adhesive coated area on said core to one side of the core slotted area, and placing a second band over the first band with an adhesive applied over the area therebetween to have the second band overlap said hinge material and to have the second and first bands become adhesively secured one to the other.
50. That method of forming plywood for a bend which comprises forming a plurality of slots across a core parallel to the axis of curvature of the intended bend, hinging one section to another of a band by a thin flexible sheet of material, folding one band section back under the other, the underfolded section being less in length than the top section, applying an adhesive over the underside of the folded section and also a portion of the underside of the top section whereby the areas of the underside of the top section covered over by the folded section and of the then inner side of the folded section are left free of adhesive, the said underfolded section having a length substantially equal to one-half of the length of the slotted area of said core, unfolding said underfolded section to swing its adhesive coated side around to be then on its top side, placing said unfolded band with its under adhesive coated area on said core to one side of the core slotted area, and placing a second band over the first band with an adhesive applied over the area therebetween to have the second band overlap said hinge material and to have the second and first bands become adhesively secured one to the other.
55. That method of forming plywood for a bend which comprises forming a plurality of slots across a core parallel to the axis of curvature of the intended bend, hinging one section to another of a band by a thin flexible sheet of material, folding one band section back under the other, the underfolded section being less in length than the top section, applying an adhesive over the underside of the folded section and also a portion of the underside of the top section whereby the areas of the underside of the top section covered over by the folded section and of the then inner side of the folded section are left free of adhesive, the said underfolded section having a length substantially equal to one-half of the length of the slotted area of said core, unfolding said underfolded section to swing its adhesive coated side around to be then on its top side, placing said unfolded band with its under adhesive coated area on said core to one side of the core slotted area, and placing a second band over the first band with an adhesive applied over the area therebetween to have the second band overlap said hinge material and to have the second and first bands become adhesively secured one to the other.
60. That method of forming plywood for a bend which comprises forming a plurality of slots across a core parallel to the axis of curvature of the intended bend, hinging one section to another of a band by a thin flexible sheet of material, folding one band section back under the other, the underfolded section being less in length than the top section, applying an adhesive over the underside of the folded section and also a portion of the underside of the top section whereby the areas of the underside of the top section covered over by the folded section and of the then inner side of the folded section are left free of adhesive, the said underfolded section having a length substantially equal to one-half of the length of the slotted area of said core, unfolding said underfolded section to swing its adhesive coated side around to be then on its top side, placing said unfolded band with its under adhesive coated area on said core to one side of the core slotted area, and placing a second band over the first band with an adhesive applied over the area therebetween to have the second band overlap said hinge material and to have the second and first bands become adhesively secured one to the other.
65. That method of forming plywood for a bend which comprises forming a plurality of slots across a core parallel to the axis of curvature of the intended bend, hinging one section to another of a band by a thin flexible sheet of material, folding one band section back under the other, the underfolded section being less in length than the top section, applying an adhesive over the underside of the folded section and also a portion of the underside of the top section whereby the areas of the underside of the top section covered over by the folded section and of the then inner side of the folded section are left free of adhesive, the said underfolded section having a length substantially equal to one-half of the length of the slotted area of said core, unfolding said underfolded section to swing its adhesive coated side around to be then on its top side, placing said unfolded band with its under adhesive coated area on said core to one side of the core slotted area, and placing a second band over the first band with an adhesive applied over the area therebetween to have the second band overlap said hinge material and to have the second and first bands become adhesively secured one to the other.

ELMO E. ALEXANDER.
